UNITED STATES PATENT OFFICE

173,154

TABLE TOP FOR MOVING AND STILL PICTURE PROJECTORS

Frank C. Harmon, Burbank, Calif., assignor to
Stainless Steel Products, Inc., Burbank, Calif.,
a corporation of California

Application February 16, 1953, Serial No. 23,638

Term of patent 14 years

(Cl. D33—14)

To all whom it may concern:

Be it known that I, Frank C. Harmon, a citizen of the United States, residing in Burbank, in the county of Los Angeles and State of California, have invented a new, original, and ornamental Design for a Table Top for Moving and Still Picture Projectors, of which the following is a specification, reference being had to the accompanying drawings, forming a part thereof.

Figure 1 is a perspective view of a table top for moving and still picture projectors showing my new design.

Figure 2 is a side elevational view thereof.
Figure 3 is a bottom plan view thereof.

I claim:

The ornamental design for a table top for moving and still picture projectors, as shown.
